G. J. HAGAN

FURNACE

Filed July 2, 1923

FIG. 1

FIG. 2

INVENTOR

George J. Hagan
by Dennis S. Wolcott
ATTORNEY

UNITED STATES PATENT OFFICE.

GEORGE J. HAGAN, OF PERRYSVILLE, PENNSYLVANIA, ASSIGNOR TO GEORGE J. HAGAN COMPANY, OF PITTSBURGH, PENNSYLVANIA, A CORPORATION OF PENNSYLVANIA.

FURNACE.

Application filed July 2, 1923. Serial No. 649,010.

To all whom it may concern:

Be it known that I, GEORGE J. HAGAN, residing at Perrysville, in the county of Allegheny and State of Pennsylvania, a citizen 5 of the United States, have invented or discovered certain new and useful Improvements in Furnaces, of which improvements the following is a specification.

The invention described herein relates to 10 certain improvements in furnaces for heating bars for sheets and also sheets formed from the bars, and has for its object a construction of furnace combining both a pair heating chamber, a sheet heating and a combustion chamber, said parts being so combined that the products of combustion will flow along the pair heating chamber from the discharging end, and after properly heating the bar, are employed for heating 20 the sheets progressively towards the discharge end of the sheet heating chamber. It is a further object of the invention to employ auxiliary means for heating the sheets, when necessary, in which case a combustion 25 chamber is so arranged that the products of combustion from the pair heating chamber will flow through such auxiliary combustion chamber and commingling with the products of combustion generated therein flow into 30 and through the sheet heating chamber. The invention is hereinafter more fully described and claimed.

In the accompanying drawings forming a 35 part of this specification Fig. 1 is a sectional plan view of a furnace embodying the improvements claimed herein and Fig. 2 is a sectional elevation, the plane of section being indicated by the line II-II, Fig. 1.

In the practice of the invention the furnace has formed therein a pair heating chamber 1 and a sheet heating chamber 2 arranged side by side and preferably having a common side wall 3. The pair heating chamber is provided at one end with suitable 40 mechanism 4 for effecting the movement of the bars through the chamber, and out through the discharge opening at the opposite end, said opening being provided with a door 5. The sheet heating chamber has an 45 opening at the same end of the furnace as the discharge opening of the pair heating chamber and the sheets are charged and dis-

charged through the opening which is provided with a door 6.

A combustion chamber 7 is located adjacent to the discharge end of the pair heating chamber, said chamber being by preference a part of or a continuation of the pair heating chamber. While fuel, either in a solid, liquid, or gaseous state may be supplied to the combustion chamber, it is preferred to employ a fluid fuel which is introduced into said chamber through an opening 8 as shown in Fig. 1. The products of combustion flow along the chamber 1 heating the bars and escape from said pair heating chamber over a bridge wall 9 or into flues 10 which branch from a main flue 11 under the hearth of the chamber 1. This main flue connects with the lower end of the vertical flue 12 which is connected by a horizontal flue 13 to the stack, the flow of products of combustion to the latter being controlled by a suitable valve or damper 14 preferably arranged in the flue 13 as shown in Fig. 2. The products of combustion flowing over the bridge wall 9 are employed for heating the sheets in the chamber 2. It may at times happen that the products of combustion flowing over the bridge wall, may not contain sufficient thermal units to properly heat the sheets in chamber 2, and hence it is preferred to employ an auxiliary heating chamber 15 through which the products of combustion from the pair heating chamber will pass and in passing through such combustion chamber will commingle with highly heated products of combustion generated in such auxiliary chamber, by the combustion of a suitable fuel, preferably fluid, injected into said chamber through an opening 16. Products of combustion flow from the auxiliary chamber 15 over a bridge wall 17 along the sheet heating chamber 2 towards the charging and discharging ends thereof, to ports 18 which are connected by branch flues to a main flue 19 under the hearth of the chamber 2. The flue 19 extends to a vertical flue 20 having its upper end connected by a horizontal flue 21 to the stack, said flue being provided with a damper 22 of any suitable construction.

The proportion of products of combustion flowing from the pair heating chamber over the bridge wall will be principally deter-

2
mined by the damper 14 in the flue 13, although such flow will also be largely influenced by the damper 22 which controls the rate of flow of products of combustion from the chamber 2.

I claim herein as my invention:

1. A furnace having in combination a bar heating chamber having openings for charging and discharging, means for moving bars from the charging to the discharging openings, means adjacent to the discharge end of the said bar heating chamber for heating said chamber, a sheet heating chamber having a charging and discharging opening and so communicating with the bar heating chamber that products of combustion will flow from the latter into the sheet heating chamber, and a stack communicating with the sheet heating chamber at a point adjacent to the charging and discharging opening of such chamber.

2. A furnace having in combination a bar heating chamber having openings at its opposite ends, means for moving bars through such chamber, a combustion chamber adjacent to the discharge end of the bar heating chamber, a flue having a regulating valve for the escape of products of combustion connected to the bar heating chamber adjacent to its charging end, a sheet heating chamber having a charging and discharging opening and so communicating with the bar heating chamber that products of combustion will flow from the latter into the sheet heating chamber, and a flue provided with a regulating valve connected to the sheet heating chamber at a point adjacent to its charging and discharging opening and connected to a stack.

40 3. A furnace having in combination a bar heating chamber having openings at its opposite ends, means for moving bars through such chamber, a combustion chamber adjacent to the discharge end of the bar heating chamber, a flue having a regulating valve for the escape of products of combustion, connected to the bar heating chamber adjacent to its charging end, an auxiliary combustion chamber connected to the bar heating chamber, a sheet heating chamber having a charging and discharging opening and so communicating with the combustion chamber that products of combustion will flow from the latter into the sheet heating chamber, and a flue provided with a regulating valve connected to the sheet heating chamber at a point adjacent to its charging and discharging openings.

4. A furnace having in combination a bar heating chamber having charging and discharging openings, means for moving bars from the charging to the discharging opening, means adjacent to the discharge end of the bar heating chamber for heating said chamber, a sheet heating chamber having a charging and discharging opening and connecting with the bar heating chamber at a point remote from such charging and discharging opening and a stack communicating with the sheet heating chamber at a point adjacent to the charging and discharging opening of such chamber and a valve controlling the flow of products of combustion to the stack.

5. A furnace having in combination a bar heating chamber having charging and discharging openings, means for moving bars through such furnace from the charging to the discharging opening, means adjacent to the discharge end of the bar heating chamber for heating said chamber, a flue having regulating valves for the escape of products of combustion connecting with the bar heating chamber adjacent to its charging end, a sheet heating chamber having a charging and discharging opening and communicating with the bar heating chamber, such communication being adjacent to the charging end of the bar heating chamber and the rear end of the sheet heating chamber and a flue provided with a regulating valve connected to the sheet heating chamber at a point adjacent to its charging and discharging openings and connected to a stack.

6. A furnace having in combination a bar heating chamber having charging and discharging openings, means for moving bars through such furnace from the charging to the discharging opening, a flue having a regulating valve for the escape of products of combustion connected to the bar heating chamber adjacent to its charging end, a sheet heating chamber having a charging and discharging opening and connected to the bar heating chamber at a point adjacent to the charging end of the bar heating chamber and the rear end of the sheet heating chamber and a flue connected to the sheet heating chamber at a point adjacent to its charging and discharging openings, and connected to the stack.

In testimony whereof, I have hereunto set my hand.

GEORGE J. HAGAN.
